UNITED STATES PATENT OFFICE.

JONAS NORTHROP, OF HOPEDALE, MASSACHUSETTS, ASSIGNOR TO WILLIAM F. DRAPER, OF HOPEDALE, MASSACHUSETTS.

LOOM-TEMPLE.

956,725.

Specification of Letters Patent. Patented May 3, 1910.

Application filed December 16, 1908. Serial No. 467,745.

To all whom it may concern:

Be it known that I, JONAS NORTHROP, a citizen of the United States, and resident of Hopedale, county of Worcester, State 5 of Massachusetts, have invented an Improvement in Loom-Temples, of which the following description, in connection with the accompanying drawings, is a specification, like numerals on the drawings representing like parts.

The invention to be hereinafter described relates to loom temples, and more particularly to that type generally known as jaw temples.

15 The aims and purposes of the present invention will best be understood and made clear from the following description and accompanying drawings of one form or embodiment of means for carrying the invention into effect, it being understood that the true scope of the invention is not circumscribed by such illustrated and described means, except as definitely pointed out in the claims.

25 In the drawings:—Figure 1 is a plan view with parts broken away showing sufficient of a loom to make clear the association of the present invention therewith; Fig. 2 is a section on the line 2—2, Fig. 1; 30 Fig. 3 is an enlarged sectional view similar to that of Fig. 2, showing the lay in its movement to forward position and the temple jaws separated; Fig. 4 is a view similar to that of Fig. 3, showing the lay as having 35 completed its forward movement and just prior to its retreat, the temple jaws being closed upon the fabric; Fig. 5 is an enlarged side view of the temple detached; Fig. 6 is a plan view of the parts shown in Fig. 5 40 with the temple rod or shank broken away; Fig. 7 is a section on the line 7—7 of Fig. 5; Fig. 8 is an enlarged detail end view of the temple jaws showing the directional engagement of the teeth with the fabric 45 and the general character of the jaw surfaces; Fig. 9 is a view of the cloth engaging face of the upper jaw; Fig. 10 is a section on line 10—10 of Fig. 5; and Fig. 11 is an enlarged fragmentary view of teeth 50 formation on the upper jaw.

55 Referring more particularly to Figs. 1, 2, 3 and 4, the loom frame 1, the breast beam 2, the lay 3, the reed 4, and the means for moving the lay in the well understood manner may be of any usual or desired character.

In the present illustration, the loom frame 1 is shown as supporting an appropriately driven sand roll 5 over which the fabric 6 passes to the usual cloth roll, and adjacent either edge portion of the fabric is the temple of the present invention disposed to engage and act upon the cloth in the manner and for the purpose as will hereinafter more fully appear. Mounted upon suitable brackets or supports 7 adjustable on the breast beam 2 by suitable means, such as the screw bolts 8, are the temple holders 9, each comprising a base portion 10, Fig. 10, and a cap 11, said base and cap each having a projecting slotted flange 12, Figs. 1 and 10, engaged by the screws 13, or other suitable means for adjustably connecting the temple holders to their respective supporting brackets, additional screws 14, 14, Fig. 1, being employed, if desired, to hold the base and cap together when the parts are removed from the breast beam. It is usual to employ a temple at each edge portion of the fabric being woven, and, aside from the fact that one is a right and the other a left temple, they are 80 or may be substantially of the same construction, so that a description of one will be sufficient. The temple holder 9 affords a support for the sliding temple rod or shank 15, Fig. 5, the stem 16 of which extends into the 85 holder and is surrounded by a spring 17 disposed between the shouldered portion 18 of the shank and the seat 19 of the holder, the construction being such that the spring normally acts to hold the temple rod or shank 90 15 and its attached temple in its position nearest the lay, with the shouldered portion 18 resting against the shoulder 20 formed on the interior of the holder. The temple rod or shank 15 extends from the holder 9 toward the lay and is provided with upper and lower temple jaws 21 and 22, one of which is movable toward and from the other in order to clamp and hold the fabric at times and release it at other times as will presently 95 appear. In the illustrated form of the invention the lower temple jaw is shown as rigid with or secured to the shank 15, and the upper jaw as movable toward and from the lower jaw, but obviously this is not essential to the true character of the invention. 100

As one means of mounting the movable jaw, the rod or shank 15 is provided with a projecting stud 23 carrying a sleeve 24 from which projects an arm 25 jointed to the up- 110

per jaw by lugs 26 and pin 27, Figs. 5 and 7, said connection with the stud 23 constituting in effect a toggle, and the construction being such that upon movement of said sleeve 24 clockwise, viewing Fig. 5, the upper jaw 21 will be forcibly moved toward the lower jaw and upon movement of said sleeve counterclockwise, viewing Fig. 5, the upper jaw will be raised. While for some purposes of the invention relative movements of the two jaws to clamp and release the fabric will be sufficient and is contemplated in some forms of the present invention, it is to be noted that the toggle operation of the movable jaw 15 gives a directional movement toward and from the fixed jaw which is the resultant of movement toward and from, and parallel with said fixed jaw, and when, as in the form of the invention illustrated, the break 20 of the toggle is toward the breast beam, any pull of the warp threads, due to shedding or otherwise, tends only to clamp the fabric more firmly. The practical advantages of the described relative movements of the two jaws will be fully appreciated by those skilled in the art when considered in connection with the lay action and its effect upon the fabric in beating up. Projecting from the sleeve 24 is an arm 28 normally under 25 the active control of a spring 29, Figs. 2, 4 and 5, interposed between a portion of said arm and a lug 30 projecting from the temple rod or shank 15, said spring being preferably seated in a suitable socket, as indicated by dotted lines, Fig. 5, formed in the arm 28, and acting to normally maintain the upper jaw in clamping relation with respect to the lower jaw. Mounted on a stud 31, or other support carried by the temple rod or shank 30, 35 is a jaw actuator 32 carrying a roll or curved surface 33, said actuator having a tail-piece 34 to be moved by the lay and normally held in position for engagement thereby by a spring 35, the construction and general relation of parts being such that upon the forward movement of the lay, as herein-after appears, the tail-piece 34 will be moved and the actuator turned about its supporting stud 31, the spring 35 serving to return the actuator to initial position, Fig. 5, as the lay retreats. The tail-piece 34 is shaped and located as shown, or otherwise so made that it will not contact with the sand roll 5 and injure the same or the temple or shuttle, even should the temple as a whole be forced rearward, as by an improperly boxed or trapped shuttle.

As well known by those skilled in the art, the lay on its forward movement carries the last shot of filling with it toward the "fell" of the cloth, and, at the moment of "beat-up," drives such filling into place closely adjacent the previous shot, which may be in a different warp shed. Such action of the lay, 60 in connection with temples heretofore in use,

has produced what is technically known as the "bump," that is, it forces the "fell" of the cloth toward the loom front causing a transversely extending roll or wrinkle in the cloth, and this roll or wrinkle follows the lay 70 backward as the latter retreats and the fabric straightens out again, thus causing objections well understood by those familiar with loom operations. To avoid this defective action, the present invention contemplates relative lay and temple jaw movements, such that, as the lay moves to and approaches its forward limit of movement the jaws will be caused to unclamp the fabric and then, prior to backward movement of 75 the lay, to again clamp it. As one form of means to this end the arm 28, Figs. 2, 3, 4 and 5, carries a jaw trip 36 pivotally connected thereto, as indicated, and comprising a toe 37 and a toe-stop 38, said toe being 80 adapted for engagement with the roll or curved surface 33 of the actuator 32, so that as the lay moves the tail-piece 34, the roll or curved surface 33 will meet the jaw-trip between the toe 37 and stop 38, raise the outer 85 end of the arm 28 and lift the upper jaw 21, as indicated in Fig. 3; and as the lay movement approaches its forward limit the jaw trip 36 will be tripped from its engagement with the roll or curved surface 33, as indicated in Fig. 4, thus permitting the spring 29 to close the jaws upon the fabric between them. A projection 39 on the arm 28 co-operating with the toe-stop 38 prevents the jaw trip 36 from swinging too far from 90 operative position when freeing itself from the roll or curved surface 33; and a stop 40 on the temple rod or shank 15 serves to limit the swing of the jaw actuator 32.

From the construction thus far described 105 it will be apparent to those skilled in the art that as the lay moves to the "beat-up" position and prior to the full forward movement thereof, it will meet the tail-piece and cause the upper jaw to move diagonally upward 110 and away from the lower jaw, thus freeing the fabric by a movement partially in the direction of the cloth travel; and as the lay reaches its full forward position, or it may be just prior thereto and before starting on 115 its backward movement, the jaw trip will free itself from the actuator and permit the upper jaw to move diagonally downward to again clamp the fabric, which is thus prevented from following the lay movement. 120 It will be noted also that at the time the fabric is released from the temple jaws it is being distended widthwise by the warp threads passing through the reed, and that while in this distended condition it is again clamped 125 by the jaws, thereby obviating much of the contraction usually found in fabrics as compared with the width of warp threads passing through the reed.

While it is desirable that the temple jaws 130

securely hold the fabric distended, it is also a matter of importance that this result be not secured at the expense of injury to the fabric itself. On the one hand the temple 5 jaws should act upon an extended area of the fabric, yet the repeated clamping and unclamping of the same portion of the fabric when the temple jaws are thus extended is liable to injure the product, and 10 especially is this the case along the selvages, which are usually more bulky and thicker than the body of the fabric. In the present invention one of the jaws is formed preferably with a plain yielding or elastic surface 15 and the other coöperating therewith is provided with teeth preferably constructed and arranged to provide a desirable holding area without at the same time subjecting either the main body of the fabric or the 20 selvages thereof to injurious treatment.

Having reference more particularly to Fig. 8, one of the jaws, the lower fixed jaw 22 in the illustrated form of the invention, is faced with an elastic or yielding substance 25 41, such as leather or the like, extending preferably, though not of necessity, over the entire surface of the lower jaw. The upper or movable jaw, Figs. 8, 9 and 11, is provided with groups of holding teeth 42, 42, 30 disposed on widely separated portions of the jaw face, the portions between said groups of teeth being plain and preferably cut away, grooved, or countersunk so as not to materially press upon the fabric when 35 the jaws are in clamping positions. In the construction shown, Fig. 9, the teeth 42 are arranged in two parallel groups or series of rows with a grooved or countersunk plain space 43 between them, and at the portion 40 of said groups, which act upon the fabric near the selvages thereof, the number of fabric engaging teeth is lessened, as by beveling off the said parallel groups at 44. From this general character of jaw construction, 45 it will be noted that an extended area of the fabric is under control of the temple, yet by reason of the blank portions on the jaw face, the part of the fabric passing therethrough is not subjected to the constantly 50 recurring clamping and unclamping action calculated to injure the thread structure, and the comparatively bulky selvages are perfectly preserved.

The individual formation of the teeth 42 55 is such that they incline with their pointed ends 48 toward the breast beam and the selvage holding edge of the jaw, as indicated in Figs. 8 and 11. As one means of securing this double inclination and thereby 60 preventing cloth contraction and any movement of the cloth through the temple due to the pull of the shedding mechanism, the teeth are produced preferably by cuts 45 extending from the selvage edge of the jaw to 65 the inner edge, and diagonal cuts 46 inter-

secting the cuts 45 in the manner shown, said cuts being preferably formed in a plate separate from the jaw and secured thereto, as by pins 47 or the like, though obviously the desired characteristics of the teeth may 70 be otherwise produced. Thus rows of holding teeth are formed in separated groups, and by the diagonal disposition of the cuts 46 with respect to the cuts 45 these rows of teeth do not act on the same longitudinal 75 portion of the fabric as it passes through the jaws, so that injury to the product by the jaw teeth is avoided.

While it is preferred to form the fabric holding teeth in the manner stated so that 80 groups will be presented for action on widely separated portions of the fabric, with a minimum number, consistent with proper holding, acting adjacent the selvages, it is apparent that the invention is not restricted 85 to the details illustrated and described, variations in these and other portions of the temple structure being contemplated by the invention, which is definitely pointed out by the claims. 90

What is claimed is:—

1. A loom temple comprising two jaws relatively movable to clamp a fabric passing between them, and means for so moving the jaws, one of said jaws being provided with a cloth engaging portion the extent of which is reduced adjacent the selvage engaging edge of the jaw to avoid injury to the cloth selvage. 95

2. A loom temple comprising two jaws, 100 and means for relatively moving them to clamp and release a fabric between the jaws, one of said jaws being provided with a plurality of groups of fabric engaging teeth, the number of teeth in the groups being reduced adjacent the selvage engaging edge of the jaw. 105

3. A loom temple comprising two jaws, and means for moving said jaws relatively to clamp and release a fabric between them, 110 one of said jaws having a plurality of fabric engaging portions, the fabric engaging extent of which is reduced adjacent the selvage engaging edge of the jaw.

4. A jaw temple for looms, comprising 115 two jaws relatively movable for clamping and unclamping a fabric between them, one of said jaws being provided with a plurality of groups of fabric engaging teeth, said groups being separated by untoothed portions of greater extent than the distance between the teeth of a group, and the extent of the groups of fabric engaging teeth being reduced adjacent the selvage edge of the jaw. 120

5. A jaw temple having one of its jaws provided with fabric engaging teeth formed by intersecting cuts, one of which extends at an inclination to the direction of cloth movement through the temple. 125 130

6. In a loom, a temple comprising a pair of jaws, a lay, and means acting as the lay moves forward to separate said jaws in a direction inclined to the plane of the fabric 40
5 passing between the jaws and to again close said jaws prior to backward movement of the lay.
7. In a loom, a temple comprising two jaws, a lay, means including a toggle acting 45
10 as the lay moves forward to separate said jaws and means to again close them prior to backward movement of the lay.
8. In a loom, a temple comprising a fixed jaw and a movable jaw, a lay, means acting 50
15 as the lay moves forward to move the movable jaw away from the fixed jaw in a direction inclined to the plane of the fabric passing between the jaws, and means to return the movable jaw to initial position prior to 55
20 backward movement of the lay.
9. In a loom, a temple comprising a fixed jaw and a movable jaw, a lay, means including a toggle acting as the lay moves forward to move the movable jaw, and means to re- 60
25 turn the movable jaw to initial position prior to backward movement of the lay.
10. In a loom, a temple comprising a pair of jaws to clamp and unclamp the fabric passing between them, a movable temple rod 65
30 carrying said jaws, a lay, and means acting as the lay moves forward to separate said jaws and to again cause said jaws to close prior to backward movement of the lay.
11. In a loom, a lay, a temple holder, a 70
35 temple rod movable in said holder, two jaws carried by the temple rod, a spring for normally holding the temple rod in operative position, and means for separating said jaws to release the fabric as the lay moves for- 75
80
- ward and means to cause said jaws to again clamp the fabric prior to backward movement of the lay.
12. In a loom, a lay, a temple holder, a temple rod movable in said holder, two jaws carried by the temple rod, a spring for normally holding the temple rod in operative 85
45 position, and means, including a toggle, for separating said jaws to release the fabric as the lay moves forward and means to cause said jaws to again clamp the fabric prior to 50
55 backward movement of the lay.
13. In a loom, a temple comprising a pair of jaws, a lay, and means acting as the lay moves forward to separate said jaws and free the fabric between them and to again 60
55 close said jaws in a direction inclined to the surface of the cloth prior to backward movement of the lay.
14. In a loom, a temple comprising jaws between which the fabric passes, a lay, means 65
60 to cause said jaws to close upon the fabric when the lay is substantially at front position, and provisions for causing any rearward pull upon the fabric to increase the clamping action of the jaws.
15. In a loom, a lay, a yieldingly supported temple comprising two jaws, and means for separating said jaws to release the fabric as the lay moves forward and to reclamp the fabric prior to its backward movement. 70
75
- In testimony whereof, I have signed my name to this specification, in the presence of two subscribing witnesses.
